CLOCK OR SIMILAR ARTICLE

George Cagen, New York, N. Y., assignor to Self Winding Clock Company, Inc., a corporation of Delaware

Application March 1, 1954, Serial No. 29,267

Term of patent 3½ years

(Cl. D42—7)

To all whom it may concern:

Be it known that I, George Cagen, a citizen of the United States and residing at New York, in the county of New York and State of New York, have invented a new, original, and ornamental Design for Clock or Similar Article, of which the following is a specification, reference being had to the accompanying drawings, forming part thereof, and in which

Fig. 1 is a front elevational view of a clock showing my new design,

Fig. 2 is a rear elevational view thereof, and Fig. 3 is a top plan view thereof.

I claim:

The ornamental design for a clock or similar article, substantially as shown.
